UNITED STATES PATENT OFFICE.

JOHN H. AGESSEN, OF HIGGANUM, CONNECTICUT.

ATTACHMENT FOR DRILL-GRINDING MACHINES.

SPECIFICATION forming part of Letters Patent No. 579,215, dated March 23, 1897.

Application filed May 6, 1896. Serial No. 590,455. (No model.)

To all whom it may concern:

Be it known that I, JOHN H. AGESSEN, a citizen of the United States of America, residing at Higganum, in the county of Middlesex and 5 State of Connecticut, have invented a certain new and useful Improvement in Attachments for Drill-Grinding Machines, of which the following is a description, reference being had to the accompanying drawings, wherein—

10 Figure 1 is a top view of the drill-bed and its immediate appurtenances. Fig. 2 is a side view of the drill-bed and its immediate appurtenances. Fig. 3 is a view of the drill-bed in cross-section on the plane $x x$, looking 15 in the direction indicated by the overlying arrow. Fig. 4 is a view of the drill-bed in cross-section on the plane indicated by the line $y y$, looking in the direction indicated by the overlying arrow. Fig. 5 is a front 20 view of the support for the drill-bed.

The object of the improvement is the production of a mechanism, device, or apparatus for use in grinding the bevels at the point of a machine-drill.

25 In the accompanying drawings, the letter a denotes the drill-bed, which, as shown in Fig. 3, is substantially a V-shaped trough to receive and to support a drill while the bevels are being ground at the point thereof.

30 The letter b denotes an adjustable end-stop for what may be called the "rear" end of the drill. It is adjustable longitudinally of the drill-bed and held fixed at any desired adjustment by the bolt and nut $c c'$.

35 The letter d denotes a set-screw for holding the drill down upon the drill-bed while it is undergoing the grinding operation. This set-screw is carried in the arm d' , which slides or may slide on the rod d^2 , being supported from 40 the drill-bed by the uprights d^1 and d^3 , and by means of this arrangement just described the set-screw d is adapted for adjustment longitudinally of the drill-bed.

The letter e denotes an adjustable gage-stop 45 for regulating the adjustment of the drill in the drill-bed rotarily. As shown, it is attached to the upright e' , having nearly vertical play in the upright d^5 and pressed upward by the spring f .

50 The letter g denotes a set-screw for holding the upright e' , and consequently the gage-stop

e , at any desired point of its permissible adjustment. It is the object and purpose of this adjustable gage-stop to enable the operator to grind the bevels at the point of the 55 drill at accurately corresponding angles. The drill having been fastened in its bed and one of these bevels properly ground, the adjustable stop is brought against a shoulder of a flute of the drill and there fastened by means 60 of the set-screw g . Then the drill is given a half-rotation, bringing the opposite flute-shoulder against the stop e . The drill is again fastened to the bed by the set-screw d and the other bevel is ground, and by reason of 65 this action the two bevels are ground at accurately corresponding angles. The up-and-down reciprocatory movement of the gage-stop e is more nearly vertical than is the surface a' within the drill-bed, wherefore it results that if the gage-stop be moved downward sufficiently it no longer projects from such surface a' , and it is a result of this construction and operation that the gage-stop is made 70 useful with drills of very small diameter as 75 well as larger ones. Now as to the support for this attachment, the letter h denotes a base having adjustable movement laterally in front of and across the face of the grinding-wheel. From it rises the socket h' . The 80 letter k denotes a post adjustably secured in said socket, so that it may have vertical adjustment. This post carries the sleeve k' , through which runs the shaft l , having free rotary movement in such sleeve. The shaft 85 l carries a fork m , which in turn carries the upright shaft n , having free rotary movement in this fork. The drill-bed is attached as a whole to the upright shaft n by means of the socket o , and it results from this construction 90 just described that the drill-bed and its appurtenances are hung and supported on what may well be called a "universal" joint.

I claim as my improvement—

1. In combination, the drill-bed a , the set-screw d adapted for adjustment longitudinally of the drill-bed, the movable spring gage-stop e , and the set-screw g , all substantially as described and for the purposes set forth.

2. In combination, the drill-bed a , the adjustable end-stop b , the set-screw d adapted

for adjustment longitudinally of the drill-bed, the movable gage-stop *e*, and the set-screw *g*, all substantially as described and for the purposes set forth.

5 3. The drill-bed *a* having the surface *a'*, in combination with the adjustable gage-stop *e* adapted to move in a line at an angle to said

surface *a'*, all substantially as described and for the purposes set forth.

JOHN H. AGESSEN.
